UNITED STATES PATENT OFFICE.

JOHN LOB MILLER, OF WELLSBURG, WEST VIRGINIA.

BOX-SCRAPER.

No. 880,745.

Specification of Letters Patent.

Patented March 3, 1908.

Application filed July 23, 1906. Serial No. 327,270.

To all whom it may concern:

Be it known that I, JOHN LOB MILLER, a citizen of the United States of America, and resident of Wellsburg, county of Brooke, 5 and State of West Virginia, have invented certain new and useful Improvements in Box-Scrapers, of which the following is a specification.

My invention relates to new and useful 10 improvements in box scrapers, and more particularly to a tool for scraping names, marks, and the like, from boxes, barrels and other wood surfaces.

The object of my invention is to provide a 15 simple, efficient and inexpensive blade-holding handle or stock adapted for co-operative employment with reversible and interchangeable scraping-blades.

A further object is to provide a wood- 20 scraping blade the construction of which is such that it is particularly adapted for taking into a wood surface.

With these and other objects in view, the invention finally consists in the particular 25 construction, arrangement and combination of parts which will hereinafter be fully described, reference being herein had to the accompanying drawings, forming a part of this specification, in which—

30 Figure 1 is a perspective view of the invention; Fig. 2 is a vertical sectional view of the blade-holding portion of the stock and the blade; Fig. 3 is a similar view of the stock with the blade removed; Fig. 4 is a front 35 elevation of the scraping-blade; and Fig. 5 is a vertical sectional view of said blade.

Referring to said drawings, in which like reference - numerals designate like parts throughout the several views—1 indicates a 40 stock or handle which may be of any suitable shape or construction having its front end reduced in size and downwardly curved, constituting a neck or shank 2. Said shank terminates in a downwardly and rearwardly 45 directed head 3 which has two transversely directed head 3 which has two transversely 50 extended, alined, communicating slots 4 and 5 through the end thereof, forming a pair of clamping jaws 6, between which a scraping-blade 7 is held by means of a screw 8 projected through said head, as shown. The lower slot 4 is made of a width which will readily accommodate said blade 7, while the upper slot is preferably made narrower in width. An inclined bearing-shoulder 9 is 55 formed at the upper extremity of the lower

slot 4, or at the point where the two slots 4 and 5 merge, against which the face of the bevel 10 leading to the extreme upper edge 11 of the blade 7 is adapted to bear or rest, the said edge 11 lying in the narrower, or 60 upper, slot 5 out of bearing contact or engagement with surfaces whereby the said edge might be injured. Said blade 7 is reversible, as shown, opposite edges 11 being provided. Said edges are made slightly 65 convex in contour and have therein a plurality of small spaced, or equi-distant, V-shaped notches 12 which extend back only partially through the length of the bevel 10, thus providing means whereby the scraping blade 70 more readily takes into, or bites into, a wood surface than as if said edges were plain. Said notches 12 are formed in the blade by striking on the reverse face of the latter, or in the face opposite the bevel 10, a series of 75 longitudinal shallow rectangular grooves or channels 13, said channels being made to extend back any desired distance from the extreme edge 11 of the blade. The bevel 10 merges with said grooves or channels 13, 80 forming said V-shaped notches, the apices of which are sharp. Further, the side edges of the teeth formed by notching the edge of the blade are sharp instead of blunt, as would be the case if said notches were 85 formed by cutting directly through the beveled edge of the blade.

The notches 12 not only admirably adapt the edge of the blade for taking into the wood but the shape and extremely limited length 90 of said notches also prevent the gouging and splintering of the wood which would be consequent were deep notches employed in the edge of the blade. When the blade is ground down in sharpening, the notches are not 95 ground out on account of the longitudinal grooves or channels 13 extending back a considerable distance from the edge.

The screw 8 is projected through the jaws 6 at a right angle to the slot 5 at a point sufficiently remote from the upper end of the slot 4 to avoid contact with the edge of the blade held by said jaws. The jaws normally stand apart a sufficient distance to admit of the ready insertion of the blade, and the 105 shank and jaws are made of a material which is sufficiently resilient to admit of said jaws being sprung together into clamping engagement with the blade.

Having thus described my invention, what 110

I claim as new, and desire to secure by Letters Patent, is—

1. The combination with a stock having its front end downwardly and rearwardly curved, of a head having two transverse intercommunicating aligned slots therein, the lower of said slots having a greater receiving capacity than the upper slot, a bearing shoulder at the upper extremity of the lower slot, a removable blade having its opposite edges beveled, said blade being mounted in said lower slot with the face of the bevel of the upper edge in bearing engagement with said shoulder, and the extreme edge, or cutting edge, lying in the upper slot, and means for clamping said blade in place. 50
2. The combination with a blade-holding handle, of a scraping-blade mounted in said handle in a forwardly-inclined position, said blade having its lower edge beveled on one side only, and having a series of longitudinal grooves in its opposite face merging with said bevel whereby alternate teeth and V-shaped notches are formed in the cutting edge of the blade, the grooves being so spaced as to leave a substantial front edge on the teeth in the line of the edge of the blade, and the teeth having their lateral edges sharpened to the apices of the notches. 60
3. A scraping-blade having a beveled cutting edge, the bevel of which is on one side only of said edge, said blade having on the side opposite the bevel a plurality of spaced parallel grooves or channels which merge slightly above the cutting edge with said bevel, said grooves being so spaced as to form alternate teeth and V-shaped serrations in said edge, each tooth having a substantial front edge in the line of the edge of the blade, and having sharpened lateral edges extending to the apices of the serrations, said cutting edge of the blade being adapted for successive grindings or sharpenings on the beveled side without lessening the depth of said serrations. 65
4. A scraping-blade having a plain un- 70

beveled face in which is provided a plurality of longitudinal grooves extending to the lower edge of the blade, the sides of said grooves being disposed in corresponding relation to the surface of the blade, a cutting edge formed by a bevel on the face of the blade opposite the grooves, said grooves being so spaced as to leave teeth, each having a substantial front edge in the line of the edge 55 of the blade, and said grooves forming V-shaped notches which adapt said edge for taking into a wooden surface. 55

5. A scraping-blade having a plain un-beveled side in which is provided a plurality 60 of longitudinal grooves or channels which extend to the lower edge of the blade and the sides of which stand in corresponding relation to the surface of the blade, said blade having a bevel on the face thereof opposite 65 to said grooved side, which bevel constitutes a cutting edge of said lower edge of the blade and V-shaped notches in said edge at the points where said grooves merge therewith, said grooves being so spaced as to leave teeth, 70 each of which has a substantial front edge in the line of the edge of the blade. 70

6. A scraping-blade having a beveled cutting edge, the bevel of which is on one side only of said edge, said blade having on the 75 side opposite the bevel a plurality of spaced parallel grooves whose sides are disposed in corresponding relation to the surface of said blade, said grooves merging with said bevel and forming V-shaped notches in said edge, 80 each of the teeth formed by the notching of the beveled edge of the blade having a substantial front edge in the line of the edge of the blade and having their lateral edges sharpened to the apices of the notches. 85

In testimony whereof I affix my signature in presence of two subscribing witnesses:

JOHN LOBMILLER.
